COMBINED SHOWER STALL LIGHT AND CURTAIN RAIL

Frederic O. Hindle, Milford, Conn., assignor of one-half
to Eben B. Woolley, Milford, Conn.

Application April 9, 1956, Serial No. 40,981

Term of patent 14 years

(Cl. D21—1)

Fig. 1

Fig. 2

Fig. 3

Fig. 4

Fig. 1 is a front perspective view of a combined shower stall light and curtain rail, showing my new design.

Fig. 2 is a front elevational view of the fixture shown in Fig. 1.

Fig. 3 is a rear elevational view of the fixture.

Fig. 4 is a right end elevational view of the fixture.

I claim:

The ornamental design for a combined shower stall light and curtain rail, as shown.
